BOOKKEEPING MACHINE

Young Hutchinson, Glendale, Calif.

Application March 13, 1939, Serial No. 261,539

2 Claims. (Cl. 282—4)

The primary object of my invention is the provision of a means for economically, efficiently and simultaneously recording the debit and credit entries of transactions, uncommon with the usual double entry system of bookkeeping, and wherein each of said entries are made independently of one another, and in different books, such as the cash book, journal and ledger.

A further and most important object of the herein invention is the provision of a means designed to set up a procedure of recording such transactions absolutely at variance with the prevailing practice, yet, assuring a systematic, speedy and economical routine of operations for positive and satisfactory results.

A further object of the herein invention is the provision of a device affording a positive means for the dual posting of all bookkeeping transactions directly to the general ledger and the elimination of the commonly employed cash book and journal, with a resultant saving in the cost of such and the pay roll burden involved in keeping the same, yet, recording in a single transaction, all of the information said eliminated books detail.

A further and highly important object is the provision of a device wherein accuracy of both debit and credit posting is assured, the one being made simultaneously with the other, and whereby each such entry must positively coincide with the other.

A further object of the device is to at all times provide a perpetual balance of accounts.

A further object of the herein invention is the provision of a light weight, substantially constructed and compactly built bookkeeping machine, foolproof and free from manipulative contrivances.

A further object of the herein invention is the provision of a bookkeeping machine, operating smoothly and quietly so as to be practically noiseless in operation, and, owing to its structural characteristics, readily cleanable.

A further object of the herein invention is the provision of a bookkeeping machine exceedingly simple in operation, so as to require no detailed study of its operation, and in keeping therewith, readily operable by any one regardless of a knowledge of bookkeeping.

A still further object of the herein invention is the provision of a bookkeeping machine embracing paper aligning means and whereby reproduction of the original recording of an entry appears on a duplicate copy in proper alignment as to marginal and space requirements.

And a further object of the herein invention is the provision of a bookkeeping machine which may readily be produced of many materials the market affords and finished in divers manner common to the painting art.

I attain these objects by the device illustrated in the accompanying drawings, in which:

Figure 1 is a plan view of the device and showing the paper comprising the general ledger sheets employed, partly broken away so as to show the underlying writing bed slots;

Figure 2 is a section on line 2—2 of Figure 1;

Figure 3 is a section on line 3—3 of Figure 2;

Figure 4 is a section on line 4—4 of Figure 1;

Figure 5 is a section on line 5—5 of Figure 1;

Figure 6 is a section on line 6—6 of Figure 3;

Figure 7 is a plan view of the device embracing typical formed general ledger sheets secured to the device in one recording direction, and

Figure 8 is a similar view with the sheets secured in another of the two possible recording directions.

Similar numerals of reference indicate corresponding parts thruout the several views, the numeral 9 thus indicating a side view of the bookkeeping machine, and comprising a top portion

10 forming a writing bed, and a frame portion consisting of side members 11 and 11' and end members 12 and 13, said side and end members forming a bottomless housing 10' (may readily be enclosed, however), and wherein are suitably attached a feed roller 14 and a take-up roller 15.

The underside of said writing bed may readily be provided with cross bracing not shown, and to which the respective paper feed rollers may be attached, with or without the bearing means shown. Moreover, the bottom edge of the side and end members may be provided with a felt liner or other resilient sound deadening means, rubber bumpers, for example, not shown, and serving to prevent marring of the object upon which the device may be placed.

The feed roller 14 is adapted to support a roll of carbon paper 16, a portion whereof is unwound from the roll and extended upwardly through a slot 17 provided in the writing bed adjacent its lower end member 12, thence longitudinally drawn and extended over and across the writing bed to its upper end 13 where it is extended

downwardly thereof through a slot 18 therein and into contact and attachment with the take-up roller 15. Thus there is established a continuous carbon paper feed arrangement atop the writing bed of the machine. The coated side of the paper facing the writing bed.

A rod or bar member 19 is suitably secured to the upper side of the writing bed immediately adjacent the slot 17 and a similar member 20 is in like manner secured immediately adjacent the slot 18. Said members perform a dual function in that they provide the respective slots with a smooth rounded edge over which the carbon paper rides, and also serve to hold the paper upwardly from the writing bed to facilitate easy 10 passage of a ledger sheet under the same.

The feed roller 14 is secured in suspended relation within the housing 10 by means of bearings 23 secured to the underside of the writing bed by any convenient means. Similar bearings 24 15 secured in like manner, suspend the take-up roller 15. Both bearing members are sufficiently resilient to readily permit placement and removal of the carbon paper rollers.

The take-up roller 15 is bifurcated at one end 20 to provide means for connecting it with the flattened end 25 of a winding stem 26 which is journaled near said end in a bearing 27 and at its other end in the side 11 of the frame 9. A knob 28 permits rotation of the stem 26 to which it is attached, and by means of which the carbon paper is simultaneously unwound from the feed roller, across the writing bed and re-wound on the take-up roller.

A bar or link member 29 provides means for carrying pins 30 and 31, which though movable in relation to the writing bed, are nevertheless fixed in relation with one another by said member 29. Said member is slidably suspended directly beneath the writing bed with the pins 30 35 and 31 each extending upwardly thereof and through a slot 32 provided in the writing bed parallel to the side 11 of the frame 9. As shown, the link is suspended by means of a rivet 33 at one end and a knob 34 at the other end, said 40 means, however, comprising but one of many which may readily be adopted to achieve identical results. Reduced portions of the rivet and knob structure respectively, are slidable within the slots 32.

Similarly a link 35 carrying pins 36 and 37 is suspended beneath slots 38 positioned parallel to the side 11 of the frame 9, a rivet 39 and knob 40 securing the same in slidable relation to the writing bed.

Obviously, said method of attachment of the shift bars may readily be varied, a groove (not shown) in the writing bed and in which the shift bar may be slidably secured, equally meeting with satisfactory results.

As best seen in Figures 7 and 8, the ledger sheet 21 employed in combination with the device is provided adjacent the left edge with holes 41 and 42. These are spaced so as to register precisely with the pins 30 and 31 respectively. Adjacent the right edge thereof, the sheet further provided with holes 43 and 44 spaced to register precisely with the pins 36 and 37 respectively.

The ledger sheet 22 also used in combination with the machine is provided adjacent its left edge with holes 45 and 50 for registration precisely with the pins 30 and 31 respectively, and adjacent the right edge thereof with holes 51 and 52 for registration precisely with the pins 36 and 37 respectively. There is thus provided a ledger sheet specifically provided for use with the machine, and the ruling, heading imprinting, and holes as aforesaid, of necessity, must be in true alignment and correct registration with the pin members, the combination of machine and paper

alone making possible the highly satisfactory results claimed.

The slideable link bar member 29 and 35 serve as a shifting means operable by gripping the respective knobs and sliding the bar therewith 5 so as to align the respective sheets in position for use. As the writing surface of one of the sheets underlies the carbon paper, a means as is hereinafter more fully explained is provided for designating the next available or unused line on said sheet, and when thus ascertained, the respective shift bars are employed to bring the several sheets in alignment with one another.

The shift means herein shown may readily be of any other type, since others suggest themselves, for example, a series of perforations and a set pin to position the sheets at a definite fixed place, roller bearing or ball race as the pivoted guiding force, and a movable pointer, all affixed to the side as well as to the top of the writing 20 surface, neither of which is shown, but all or any of which would serve the purpose are feasible.

When either form is secured to the device by attachment to the pin members 36 and 37, the left hand side of that sheet should always be 25 placed under the carbon paper. Conversely, when either form is secured by attachment to the pin members 30 and 31, the right hand side of said sheet should always appear over the carbon paper. Thus, both sides of the same writing surface on each page comprising the sheets are separably adaptable to use, and in this, independently of one another. In either case, one sheet 30 always overlaps the other with the carbon paper therebetween.

In its simplicity, ease of operation, and manner of application, the device differs in many respects from bookkeeping machines in common use. Recognizing the fundamental law of accounting that for every debit there is a credit in 40 identical amount, and vice versa, the principal objective of the device then is to make both of said entries at one and the same time. Speed and absolute accuracy is thus attained. In recording the respective accounting transactions 45 of a business, any business, the sheets, herein identified as general ledger sheets are employed. All posting can be made directly from bank deposit entries and check stubs for cash items, and from invoices, sales sheets, etc., for items other than cash. Copying with its ever present possibility of transposition of numbers, and the time and expense of making cash and journal entries, together with the cost of such books, may therefore be eliminated. They may, however, be 55 maintained, if desired. As the entries in said books are made from said facts in the first instance, it is reasonable to believe that the use of said items as a direct means of establishing the general ledger, coupled with the elimination 60 of such intermediate books, will establish as satisfactory a record. Moreover, by simultaneously recording both debit and credit entries, the record is bound to be in balance. Using the same figures for both entries, one an exact duplicate 65 of the other, it could not be otherwise.

In operation, two sheets are used. One for the account to be debited, the other for that to be credited. Each sheet has two separate writing surfaces, each is columnar ruled as is disclosed 70 in Figures 7 and 8 respectively, and as is more particularly indicated by the numerals 46 and 47, and 48 and 49 respectively, the left side providing space for the recordation of debit entries, the right side, credit entries. Thus one sheet covers 75

the carbon paper and is attached to the left side of the machine in attachment with the shifting bar thereto provided, with the machine facing the operator. The other sheet is positioned under 5 the carbon paper and is attached to the right side of the machine affixed to the shifting bar there provided. The sheets are used interchangeably as required to properly debit and credit the respective account each sheet represents. With 10 sheet 21 secured to the left of the machine and on top of the carbon paper, sheet 22 would be under the carbon paper and in attachment with the right side of the machine. With sheet 21 thus positioned, the right writing surface 47 thereof 15 is used since it covers the carbon paper, and any recording thereon made would be duplicated on left writing surface 48 of sheet 22 positioned under the carbon paper. With sheet 22 positioned to the left shift bar and overlying the carbon 20 paper, the right writing surface 49 thereof will comprise the surface written upon, and directly thereunder with the carbon paper therebetween, will be a duplicate of the recording made on the left writing surface 46 of the sheet 21. Thus both 25 writing surfaces on each sheet have their respective uses.

When thus positioned for use, it follows that whatever may be written on the upper sheet will be duplicated by means of the carbon paper on 30 the lower sheet. In as much as the writing surface of said lower sheet is covered entirely by the carbon sheet, to facilitate proper alignment with the next open or unused line or space appearing on said sheet, the operator either at the 35 time of completion of all entries he makes on each sheet, or just before inserting the same on the writing bed makes a mark in a column provided on the sheet to indicate the next open line or space, so that when the sheet is in place under 40 the carbon paper, said mark will show immediately adjacent the carbon paper, this enabling the operator to shift the paper by means of the respective shift bars so that what is written on the first available line of the upper sheet will 45 appear in the first available line on the lower sheet.

While I have shown a plurality of shift bars, it should be obvious that one would serve the purpose equally as well, and, in which case, in substitution of the other, the pin members thereon provided would be secured to the machine in fixed relation thereto so as to hold the paper thereon secured in stationary relation to the other sheet, shifting of the single bar as readily 55 aligning the paper sheet thereto secured with that secured to the stationary pins.

Obviously, the columnar ruling of the sheet and headings may be supplied as the needs require. As shown there is provided a column for 60 indicating the "Date," "Description," "Account number—Debit—Credit," "Folio," "Deductions," the three spaces provided permitting use for indicating such allowances taken or granted as "State unemployment insurance, Social Security 65 payments, pay roll, discounts, trade allowances," etc., "Debits," "Credits," "Auditor's check" and "Operator's mark" as hereinbefore explained.

When sheet 21 is used above the carbon paper, deductions taken are written thereon. When sheet 22 is so used, the deductions granted are written thereon.

A transposition of figures is very unlikely as the operator is looking directly at the source of entry when posting and therefore does not carry the corresponding entry in his mind as is common with bookkeeping methods in general.

Speed, accuracy and a perpetual balance, plus 10 economy in use are assured. The machine is light in weight, easily carried about, practically unbreakable and foolproof.

I am aware that slight modifications may from 15 time to time be made in the details of structure illustrated without departing, however, from the scope of the present invention, and as defined in the claims which are appended hereto.

Hence, I do not limit my present invention to the exact description of construction herein disclosed, but what I do claim is:

1. In a bookkeeping machine, a writing bed, relatively slidable members disposed adjacent opposite edges of said bed, means for slidably securing said members to said bed, upstanding pins 25 on said members adapted to be inserted thru apertures of sheets of paper and positioned so that said sheets may be supported on said bed in overlapping relation whereby matter written on the uppermost sheet will be copied on the 30 lower sheet when carbon paper is disposed between said sheets, handles mounted on slidable members for effecting adjustment thereof on the bed, and means for holding carbon paper on said bed between said sheets and subject to adjustment 35 relative to the sheets without changing the positions of said sheets, and including members over which the carbon paper extends and which elevate the said paper from the bed to facilitate insertion of the lowermost sheet between said 40 carbon paper and said bed.

2. In a bookkeeping machine, a writing bed, relatively slidable members disposed adjacent opposite edges of said bed, means for slidably securing said members to said bed, outstanding 45 pins on said members adapted to be inserted thru apertures of sheets of paper and positioned so that said sheets may be supported on said bed in overlapping relation to one another and whereby a writing made on the uppermost of said 50 sheets will automatically appear on the lower of said sheets when carbon paper is positioned therebetween, handles mounted on slidable members for effecting adjustment thereof on said bed, means for holding carbon paper between said 55 sheets on said bed, said carbon paper subject to adjustment relative to said sheets in fixed relation to said bed, members raising said carbon paper slightly above said bed in elevated position therefrom and facilitating insertion of said paper 60 sheets in said bed with said carbon paper therebetween, said bed being provided with slots adjacent opposite sides, said slidable members being mounted on the under side of the bed and having the upstanding pins slidable in said slots. 65
